AMALGAMATOR

George Opincar, Blanca, Colo.

Application June 17, 1938, Serial No. 214,299

3 Claims. (Cl. 209—43)

This invention relates to amalgamators and more particularly to a machine or apparatus of this character for use in the recovery of precious metals, such as gold and the like, from crushed ore or placer material.

The invention has for its prime object to simplify and make more practical separating and concentrating apparatuses whereby to get a better separation of the material and a greater and more valuable recovery of the precious metal.

Other particular objects and advantages to be attained will hereinafter more fully appear.

The invention consists in the novel general structure and in the parts and combinations and arrangements of parts thereof, as hereinafter described and set forth in the appended claims, reference being had to the accompanying drawing illustrating a practical adaptation of the invention and in which:

20 Figure 1 is a view of the apparatus partly inside elevation and partly in longitudinal section;

Figure 2 is a top plan view of the apparatus; Figure 3 is a fragmentary view, on an enlarged scale, partly in elevation and partly in longitudinal section, showing details of the sluice box structure for the release of the material held by the riffles, the releasing doors being in closed position; and

Figure 4 is a view similar to Figure 3, showing the material-discharging doors in opened position.

Referring now to the drawing, the numeral 10 indicates generally the under frame of the machine, said frame being of any suitable structure and shown more or less conventionally as comprising horizontal longitudinally extending top rails 11 mounted on uprights 12 and braced by diagonal stays 13.

20. Mounted on the under frame 10 is an inclined longitudinally extending sluice box, designated generally by the numeral 14, and comprising a bottom 15, which is generally flat throughout its length, and having side walls 16, said sluice box 25 being shown more or less conventionally except as to certain essential details which will be hereinafter more fully described.

As shown, the discharge end of the sluice box 14 is supported directly on the adjacent end of the under frame 10, as at 17, the feed end of the box being raised from the opposite end of the under frame and supported on a suitable cam device 18 provided with an operating handle 19 for convenience in adjusting said cam device to vary the degree of inclination of the sluice box.

to control the flow of the material under treatment in the apparatus.

At the feed end of the sluice box is a traveling screen 20, of endless belt type, said conveyor comprising a pair of side belt members 21 which are cross connected by a plurality of spaced bars 22, one flight of the screen traveling over the top of the sluice box and the other flight beneath the box. The belt is supported at one side of the sluice box on a roller 23 journaled in brackets 24 attached to the adjacent side wall 16 of the box and at the opposite side of the box on a roller element 25 fixed on a drive shaft 26, said drive shaft being journaled at opposite sides of the endless screen 20 on bracket members 27 provided therefor on the adjacent side wall 16. As shown, the shaft 26 is provided with a pulley 28, which is connected to a suitable source of power (not shown) by a belt 29, and for operating other elements of the apparatus, to be later described, said shaft 26 is extended in proximity to the discharge end of the apparatus where it is journaled in a supporting bracket 27' similar to the brackets 27 which support the end portion of the shaft on which the roller element 25 for the endless screen 20 is mounted.

Adjacent the feed end of the sluice box 14 and slightly overhanging the endless screen 20 is a delivery chute 30 for feeding the material to the apparatus for treatment, the material being received on the upper flight of the screen 20, and such particles of the material which are not small enough to pass between the bars 22 of the screen are carried by the upper flight of the screen and discharged at one side of the apparatus to be disposed of as waste material or used for any commercial purpose for which it is suitable.

It is here noted that the material may be placed in the usual pulpy and flowable condition by the addition of water or suitable liquid compound just prior to being fed into the sluice box or immediately thereafter, and to supply the necessary solution containing such ingredients as cyanide or certain acids generally employed in the treatment of the material, a tank 31 is located above the discharge end of the chute 30 for containing the solution, said tank being provided with a series of pet cocks or other suitable valved outlets 32 whereby the solution from the tank is permitted to drip upon the material as it passes from the chute 30 onto the traveling screen 20.

As the material deposited on the bottom of the sluice box 14 through the screen 20 flows along the sluice box, it passes first over a series of transverse riffles 33 which are in the form of 55

vertically disposed flat rib members or plates projecting upwardly from the bottom of the sluice box and extending from side wall to side wall thereof, said riffles projecting high enough from the bottom of the sluice box to provide substantial abutments for the arrest of the heavier particles which are precipitated in the flowing pulp but permitting the lighter particles to flow on with the liquid content of the pulp for further treatment in the apparatus as will be presently described.

The accumulated material, which is arrested by the riffles 33, is discharged through openings provided therefor in the bottom of the sluice box 14 adjacent each of the riffles, said openings being normally closed by trap doors 34 which open downwardly so as to discharge the material into a receptacle in the form of a pan 35 which is supported on the under frame 10 and is of a size so as to be common to all of said discharge openings in the bottom of the sluice box, said pan 35 being divided into separate compartments to receive the material from the respective discharge openings in the sluice box, or not, as may be desired. Obviously, while the discharge openings are elongated and extend from side wall to side wall of the sluice box, they are relatively narrow in width but sufficiently wide to permit ready passage of the heavy particled material therethrough, there being preferably a floor space between the discharge opening and the riffle next ahead thereof.

The trap doors 34 may be opened periodical-
ly, either manually or automatically under power. For this purpose, each trap door is mounted on a hinge rod or shaft 36, which projects at opposite ends beyond the adjacent side walls of the sluice box and is provided with crank arms 37, the crank arms of the respective shafts 36 being connected by links 38 on each side of the sluice box, one of the links being operated by a hand lever 39, which is pivotally mounted, as at 40, on the adjacent side wall 16 of the sluice box. The power means for operating the trap doors 34, as shown, comprises a disk 41 rotatable at the side of the sluice box opposite to that on which the hand lever 39 is mounted, said disk 41 having a peripheral cam projection 42 to engage the adjacent end of the connecting link 38 for the respective crank arms 37 on the ends of the hinge shafts 36 for the doors 34 at that side of the machine. The disk 41 is mounted on a shaft 43 journaled in bearings provided therefor on the under frame 10, said shaft having a pulley 44 which is connected by a belt 45 to a driving pulley 46 fixed on a shaft to be later described and having a gear connection with the main driving shaft 26 hereinbefore described.

Beyond the series of riffles 33 the sluice box 14 is provided with a series of transverse troughs or ditches 47 in its bottom, said troughs or ditches being semi-cylindrical in form and extending from side wall to side wall of the sluice box. Extending from end to end of each of the troughs or ditches 47 is a rotatable retarding element 48 mounted on a shaft 49 having a beveled gear 50 at its end in mesh with a similar gear 51 fixed on the driving shaft 26, by which provision the several elements 48 are simultaneously operated, and in this connection, it is here noted that the driving pulley 46 for the cam disk 41 is mounted on one of the shafts 49 so that the disk 41 rotates simultaneously with the respective retarding elements 48 in the several troughs or ditches 47 but with a predetermined ratio in the rota-

tion of the disk 41 whereby the respective trap doors 34 are intermittently opened to discharge the heavier and larger particled material at regular intervals from in front of the riffles 33.

The retarding elements 48, as shown, comprise rods which are coiled about the respective shafts 49 and fastened at their ends and preferably at points throughout their length to the shafts so as to rotate therewith, the diameter of the coils being slightly less than that of the respective troughs or ditches 47, said troughs or ditches being filled with mercury and the rotating spiral retarder elements 48 working as they do through the body of mercury not only collecting on their surfaces the flour or fine floating gold but also forcing larger particles of the metal into the mercury, while the particles not thus retarded and deposited upon the element 48 or into the body of mercury pass on with the water successively to the next trough or troughs 47 where the same action occurs.

At the discharge end of the apparatus the sluice box 14 is provided with a transverse trough or ditch 52, which is also of semi-cylindrical cross section similar to the troughs or ditches 47. This trough or ditch 52 is provided with a different form of retarder element 53 comprising a shaft 54 provided with a multiplicity of radial pins 55, the shaft being driven by a miter gear connection with the driving shaft 26 similar to the gears 50 and 51 which drive the respective shafts 49 of the retarder elements 48.

The endmost trough or ditch 52 receives any of the mercury which may possibly pass beyond the next adjacent trough or ditch 47, the rotating retarder element 53 functioning to effectively withhold the amalgam in said trough 52 and recover such of the free gold which passes beyond the several mercury-containing troughs or ditches 47, while the tailings are discharged from the apparatus over a chute 56.

From the foregoing it is obvious that there is an effective separation of the coarser waste particles of the material as fed initially into the machine and that prior to the treatment of the material in the several mercury troughs or ditches such of the material that accumulates against the respective riffles 33 is discharged either manually and by automatic power means into a receptacle and the material so discharged may be treated by extraneous means for the recovery of such part thereof that may be of any commercial value. However, the prime recoveries of value are from the amalgam which is removed time and again from the respective troughs or ditches 47 and 52 and from the accumulations on the respective retarder elements 48 and 53.

Obviously, the general structure and parts of the apparatus may be modified in many respects within the spirit of the invention as defined by the appended claims. The invention, therefore, is not limited to the specific construction and arrangement shown in the accompanying drawings.

What is claimed is:

1. In an amalgamating apparatus of the character described, a sluice box provided with a series of transverse riffles inwardly from the material-receiving end thereof, said riffles being spaced a considerable distance apart and the bottom of the sluice box having relatively narrow discharge openings extending from side to side of the box, there being one of said openings next adjacent each riffle at the rear thereof, the respective discharge openings being normally closed.

5 by trap doors substantially flush with and completing the continuity of the bottom proper of the sluice box, connected operating means for effecting the simultaneous opening of said trap doors, power means operating to intermittently engage said connected operating means and thereby effect the opening of the trap doors, and manually operable means for effecting the actuation of said connected operating means to open 10 said trap doors at will.

10 2. In an amalgamating apparatus of the character described, a sluice box provided with a series of transverse riffles inwardly from the material-receiving end thereof, said riffles being 15 spaced a considerable distance apart and the bottom of the sluice box having relatively narrow discharge openings extending from side to side of the box, there being one of said openings next adjacent each riffle at the rear thereof, the respective discharge openings being normally closed 20 by trap doors substantially flush with and completing the continuity of the bottom proper of the

sluice box, a subjacent common receptacle located beneath said sluice box in receiving relation to all of said discharge openings, connected operating means for effecting the simultaneous opening of said trap doors, power means operating to intermittently engage said connected operating means and thereby effect the opening of the trap doors, and manually operable means for effecting the actuation of said connected operating means to open said trap doors at will. 10

3. In an amalgamating apparatus of the character described, a sluice box having a transverse semicylindrical mercury trough depressed in the bottom thereof, and a rotary retarder element working in said trough, said retarder element 15 comprising an axial shaft and a rod coiled to form a helix surrounding the shaft concentrically in spaced relation to the shaft and with its convolutions spaced apart, said helix being attached to the shaft to rotate therewith and being of a 20 diameter approximately that of the trough.
